G. SULZER.

MULTISTAGE CENTRIFUGAL PUMP.

APPLICATION FILED MAR. 14, 1911. RENEWED JULY 7, 1914.

1,129,139.

Patented Feb. 23, 1915.

UNITED STATES PATENT OFFICE.

GEORG SULZER, OF HARRISON, NEW JERSEY, ASSIGNEE TO HENRY B. WORFINGTON,
OF NEW YORK, N. Y., A CORPORATION OF NEW JERSEY.

MULTISTAGE CENTRIFUGAL PUMP.

1,129,139.

Specification of Letters Patent. Patented Feb. 23, 1915.

Application filed March 14, 1911, Serial No. 614,307. Renewed July 7, 1914. Serial No. 849,565.

To all whom it may concern:

Be it known that I, GEORG SULZER, a citizen of the Republic of Switzerland, residing at Harrison, county of Hudson, and 5 State of New Jersey, have invented certain new and useful Improvements in Multistage Centrifugal Pumps, fully described and represented in the following specification and the accompanying drawings, forming a 10 part of the same.

The especial object of the present invention is to provide a simple two-stage centrifugal pump, which shall be efficient, durable, cheap of manufacture, and not liable 15 to get out of order, and requiring no skilled attention, the pump being especially adapted for house tank service or other uses where the pump is not run by a skilled engineer.

In the accompanying drawings forming 20 a part of this specification, there is shown for the purpose of illustration, a two-stage pump of the preferred form embodying the invention, and this pump will now be described in detail, and features forming the 25 invention then specifically pointed out in the claims.

In the drawings, Figure 1 is a vertical central section of the pump. Fig. 2 is a 30 sectional elevation on the line 2 of Fig. 1, partly broken away to show the construction. Fig. 3 is a partial horizontal section on the line 3 of Fig. 2. Fig. 4 is a partial section on the line 4 of Fig. 1.

Referring to the drawings, A A' are 35 the first and second stage impellers, carried by the shaft B, these impellers being reversed so as to balance the pump without the aid of special balancing devices. The casing is shown as formed of a suction head 40 C and delivery head D with the partition plate E separating the impeller chambers, these parts conveniently being bolted together to form a casing, as shown, and the two heads carrying respectively the suction 45 connection 10 and delivery connection 11.

The shaft B is mounted in any common or suitable manner in the heads C, D, and the heads of impellers A A' preferably abut and run in an opening in the partition plate 50 E as shown, no packing between the impeller chambers being required, and support of the shaft in the partition plate E being thus provided.

In assembling the parts it is obvious that 55 the impeller A' may first be slipped in place

in the head D, the partition plate E then put on, the impeller A slipped in, the impellers then locked up against the shoulder on the shaft B, and the suction head C then put in place and the parts of the casing 60 bolted together.

The first impeller A delivers from its volute formed by wall 12 on the inner side of head C to passage 13 at the end of the volute, which extends through the partition 65 plate E and connects with suction passage 14 in head D, for impeller A', and the second impeller A' delivers through its volute formed by wall 15 on the inner side of head D to the delivery 11. Ample space is 70 provided for the cross passage 13 outside the points of the volutes, without increasing the cross dimension of the pump beyond that required for the capacity desired.

It will be seen that the invention provides 75 a pump excellently adapted for house tank and similar service where a very small pump that is simple, durable, and has no parts to get out of order, or requiring skilled 80 attention, is desired.

What I claim is:

1. A centrifugal pump having two single suction impellers arranged back to back with their single suctions in opposite directions and with volute deliveries, and a partition between the pump chambers, the volute of one impeller delivering through a cross passage directly to the suction passage of the other impeller to form a two-stage pump. 90

2. A centrifugal pump having two single suction impellers arranged back to back with their single suctions in opposite directions and with volute deliveries, and a partition plate between the pump chambers, the volute of one impeller delivering through a cross passage in the partition plate to the suction passage of the other impeller to form a two-stage pump. 95

3. A centrifugal pump having two single suction impellers arranged back to back with their single suctions in opposite directions and with volute deliveries, and a partition plate between the pump chambers, the volute of one impeller delivering through a cross passage in the partition plate to the suction passage of the other impeller to form a two-stage pump, and a casing formed of a suction head and delivery head secured together with the partition plate between them 105 110

and forming respectively the volutes for the first and second impellers.

4. The combination with reversed impellers A, A', of partition E having cross passage 13 from the chamber of impeller A, suction passage 14 for the impeller A' connecting with passage 13, and suction and delivery heads forming volute impeller chambers on opposite sides of the partition.
- 10 5. The combination with reversed impellers A, A', of partition E having cross passage 13 from the chamber of impeller A, suction passage 14 for the impeller A' con-

necting with passage 13, suction and delivery heads forming the impeller chambers 15 on opposite sides of the partition, and having inner volute walls 12, 15 surrounding the impellers.

In testimony whereof, I have hereunto set my hand, in the presence of two subscribing 20 witnesses.

GEORG SULZER.
